UNITED STATES PATENT OFFICE.

SAMUEL KOPS, OF NEW YORK, N. Y., ASSIGNOR TO KOPS BROS., OF NEW YORK, N. Y., A FIRM.

CLASP FOR GARMENT-SUPPORTERS.

No. 918,168.

Specification of Letters Patent.

Patented April 13, 1909.

Application filed May 18, 1908. Serial No. 433,447.

To all whom it may concern:

Be it known that I, SAMUEL KOPS, a citizen of the United States, residing in the borough of Manhattan, city, county, and State of New York, have invented an Improvement in Clasps for Garment-Supporters, of which the following is a specification.

My invention relates to an improvement upon the structure shown and described in my application for Letters Patent in the United States, Serial No. 380,206, filed June 22, 1907, with the object of simplifying the clasp and at the same time maintaining an equal efficiency.

In carrying out my invention I employ in combination with a flat tongue member of metal having a fabric engaging slot at one end, a plate member having jaws receiving and engaging the said tongue member and a removable member of yielding material such as rubber coming between the upper face of the plate member and the juxtaposed and under surface of the tongue member in use, and in so doing effecting an additional hold or grip upon the interposed fabric. I prefer to employ a tapering tongue member and a slotted jaw plate member. This removable member of yielding material is preferably in the form of an endless band of rubber stretched over the jaw plate member between boundaries or limits provided therefor in the direction desired. This band may extend across the plate in the line of its width, or lengthwise of the plate between the jaws; recesses or apertures being provided to receive and locate the same.

In the drawing, Figure 1 is an elevation, Fig. 2 a vertical longitudinal section showing the devices of my improvement, Fig. 3 is an elevation of the slotted plate member alone. Figs. 4, 5, 6, 7, 9 and 10 are elevations of jaw plate members showing forms of my invention and Fig. 8 is a vertical central section through the form shown in Fig. 7 all of which are hereinafter more particularly described.

a represents the main webbing of the hose supporter connected in the usual manner to a slotted plate *b*.

c represents a tape or webbing connected with one of the slots of the plate *b*.

d represents the tapering tongue member and *d*¹ a slot at one end of the same. This slot receives a part of the tape or webbing *c* which in turn is connected to the plate *b* and

this same tape or webbing *c* extends to connection with the slots of the slotted jaw plate member *e*. This latter is provided with parallel oppositely disposed slots 2 3 and with intermediate side jaws *e*¹ *e*² adapted to receive between them the tapering tongue member *d* in gripping the fabric of the hose or other article of wearing apparel. This slotted jaw plate member is preferably constructed so as to provide an appreciable space between similar ends of the jaws and one of the slots. I have shown in the drawing Fig. 3 that this space is at the lower portion of the plate member between the lower ends of the jaws *e*¹ *e*² and the slot 2, while in Fig. 4 I have shown this space at the upper part of the plate member. I provide a strip of yielding or flexible material *f*, preferably a strip of rubber,—which is sprung over the middle of the plate and surrounds the same at either of these points, coming between the ends of the jaws and one of said slots. I may employ either or both of these bands. This provides a yielding surface which comes next to the under surface of the tapering tongue member when the same is passed between the jaws *e*¹ and *e*², consequently when the fabric of the hose or other garment is placed between the slotted jaw plate member and the tapering tongue member, the same will not only be gripped between the jaws and the edges of the tapering tongue member, but between the under surface of the tapering tongue member and the surface of the yielding material, there being thus several points of grip between the parts for more securely engaging and holding the fabric in the grip of the clasp.

In Figs. 5 and 6 I have illustrated the outer bars *e*³ of the plate *e* as cut through and the inner plate edges of the slots as centrally notched and bands of flexible yielding material *g* *g*¹ differing in width, as received in said notches and stretched lengthwise over the slotted jaw plate *e* between the jaws. The outer bars *e*³ as cut through permit of the passage into the slots of the ends of the flexible material which by preference are endless bands.

In the forms of my invention shown in Figs. 7 and 8, the slotted jaw plate member *e* is centrally apertured—the hole being of appreciable size—and I employ a button of flexible material *h* formed with a stem to fit this hole and thin heads at opposite sides.

This is adapted to be forced to place as shown in these figures to perform the same holding function as described with reference to the other figures of the drawing.

5 In the form of my invention shown in Figs. 9 and 10, Fig. 9 shows the structure of either Fig. 5 or 6 combined with that of Fig. 3, while Fig. 10 shows the structure of either Fig. 5 or 6 combined with that of both Figs. 10 3 and 4.

I also do not limit myself to placing the strip of material *f* at the place indicated as it may be placed at the opposite end of the jaws.

15 The device of my improvement is all the more efficient because the grip between the parts is effective to its full extent at the moment that the jaws of the plate bind firmly with the tapering tongue member 20 when the same is in position, and the material of the garment interposed.

I claim as my invention:

1. A clasp for garment supporters, comprising a tapering tongue member, a slotted jaw plate member receiving the tongue member, and a strip of yielding material extending around the metal of the plate member at one end of the jaws and coming between the

surface of the plate member and the under surface of the tapering tongue member.

2. A clasp for garment supporters, comprising a tapering tongue member, a slotted jaw plate member receiving the tongue member, said latter member being so constructed as to have a space between the jaws at one end and the adjacent slot, and a strip of rubber surrounding the plate member between the jaws at one end and the adjacent slot and coming between the surface of the jaw plate and the under surface of the tapering tongue member.

3. A clasp for garment supporters, comprising a tongue member, a jaw plate member receiving the tongue member and a removable yielding and flexible member adapted for attachment to the jaw plate member in the desired position and having a part extending beyond the surface plane of the said member to come in contact with the under side of the tongue member.

Signed by me this 12th day of May 1908.

SAMUEL KOPS.
